(57) **CLAIM**

The ornamental design for a cup with a lighted spinning top insert, as shown and described.

DESCRIPTION

FIG. 1 is an elevation view of an embodiment of my new design for a cup with a first or upper compartment for holding liquids and a "round" spinning top insert. As shown in FIG. 1, the "round" spinning top insert is located and fits within a lower or second compartment of the cup body.

FIG. 2 is an elevation view of another embodiment of my new design for a cup with a first or upper compartment for holding liquids and a "square" or "Dradel-type" or spinning top insert. As shown in FIG. 2, the "Dradel" spinning top insert is located or fits within a lower or second compartment of the cup body.

FIG. 3 is a bottom plan view of FIG. 1 of this cup invention with the "round" spinning top insert; and,

FIG. 4 is a bottom plan view of FIG. 2 of this cup invention with the "Dradel-type" spinning top insert.

The broken lines are included for the purpose of illustrating environment and form no part of the claimed design.
